UNITED STATES PATENT OFFICE.

ROBERT LELAND KINCAID, OF SYRACUSE, NEW YORK.

WASHING-MACHINE.

1,378,177.

Specification of Letters Patent. Patented May 17, 1921.

Application filed December 6, 1919. Serial No. 342,899.

To all whom it may concern:

Be it known that I, ROBERT LELAND KINCAID, a citizen of the United States, and a resident of Syracuse, in the county of Onondaga and State of New York, have invented 5 a certain new and useful Washing-Machine, of which the following is a specification.

This invention has for its object a washing machine which is particularly simple in 10 construction, composed of a minimum number of compactly arranged parts and which is highly efficient and durable in use; the invention consists in the combinations and constructions set forth and claimed.

15 In describing this invention, reference is had to the accompanying drawings in which like characters designate corresponding parts in all the views.

Figure 1 is a sectional view of a washing 20 machine embodying my invention.

Fig. 2 is a sectional view on line 2—2, Fig. 1.

Fig. 3 is a plan view of the diaphragm.

Fig. 4 is a section on line 4—4, Fig. 3.

25 Fig. 5 is a detail view of the rim of the diaphragm.

Fig. 6 is a sectional view on the plane of line 6—6, Fig. 2.

This washing machine comprises generally, a receptacle or tub, a vibratory diaphragm detachably mounted in the tub and having a rim, the receptacle and the rim co-acting to hold the diaphragm from bodily displacement and also holding the rim from 30 vibratory movement, and means connected to the central portion of the diaphragm to vibrate the same while its rim is held stationary.

1 designates the receptacle or tub which 40 may be of any suitable form, size and construction.

2 designates the diaphragm which is here shown as a disk of flexible material as canvas formed with eyes or metal lined perforations 3 through which water washes during the vibrations of the diaphragm.

This diaphragm is provided with suitable metal rims 4 to which the margin of the disk is connected, the rim being expandible and 50 contractile. As here shown it is in the form of a split metal ring and having its ends connected by a link 5 pivoted at each end to one end of the ring. As here shown, this rim is also formed with an inwardly extending loop 7 diametrically opposite its ends,

this loop facilitating the expandible and contractile feature and also forming a passage for the part of the actuating mechanism as will be hereinafter described. The rim is also formed with a pair of handles 8 by 60 means of which the diaphragm can be lifted out of and placed into the receptacle.

In the illustrated embodiment of my invention, the receptacle is formed with an internal annular groove 9 for receiving the 65 rim 4, and after the diaphragm has been placed in the receptacle and pushed down until the rim enters or snaps into the groove, the rim is expanded into the groove, the link 5 coming into the arc of the ring and locking the ring expanded. The diaphragm is vibrated by suitable mechanism preferably connected to the lower side of the diaphragm.

The diaphragm is also formed with valve 75 controlled return passages 10 for the water. These passages are formed near the margin of the diaphragm and the valves or flaps 11 on the upper side of the disk covering the passages 10. When the diaphragm moves 80 downwardly the water is pushed up through the passages 10 raising the flaps 11 and also through the perforations in the diaphragm, but when the disk is moving upwardly the flaps close the passages and compel the 85 water to pass through the clothes on the diaphragm. The receptacle is also formed with return pipes 12 connecting the space below the diaphragm with that above the diaphragm. Thus, during downward movement of the diaphragm the water is forced 90 up through the pipes 12.

The perforations of the diaphragm are more or less obstructed by the clothes on the diaphragm and hence the marginal passages 10 or the return pipes 12 are provided to avoid stopping or retarding of the machine by reason of the water not being displaced fast enough below the diaphragm.

As here shown the mechanism for actuating the diaphragm consists of a lever arm 13 located within the receptacle and pivoted at 14 to a support 15 as a casting located in the receptacle, the lever having a short arm 16 connected to the actuating mechanism to 100 be presently described, and another arm connected by means of a link 17 to the intermediate part of the diaphragm 2.

As here shown, the intermediate part of the diaphragm is formed with a metallic 110.

center piece having a depending bearing 18 to which the pivot 19 of the upper end of the link 17 is connected.

The actuating means for the lever 13 com-

- 5 prises a suitable motor 20 here shown as mounted on the frame 21 of the machine which frame supports the tub or receptacle, the upwardly extending shaft 22 having a gear as a worm gear 23 at its lower end 10 meshing with the worm 24 on the motor shaft 25 and having a bevel gear 26 at its upper end meshing with the bevel gear 27 mounted on a shaft 28 journaled in the bearing 29 supported by the upright wall of 15 a receptacle, a frame extending upwardly along said wall, the shaft 28 extending to the inside of the receptacle and having a crank arm 30 thereon.

A link 31 connects the crank pin of the

- 20 arm 30 and the short arm 16 of the lever 13. This link extends through the loop 7 of the rim 4 of the diaphragm as does also a casting inclosing this link and the crank arm 30. Obviously during actuation of the motor, 25 the link 31 will be reciprocated moving the lever arm 13 upwardly and downwardly and oscillating the diaphragm. The clothes are placed on the diaphragm and the water placed in the tub to a suitable level and 30 during the oscillation of the diaphragm the water is passed to and fro through the clothes on the diaphragm through the dia- phragm and perforations therein. The dia- 35 phragm is readily placed in position either alone or with the clothes thereon by means of the handles 8.

- The shafts 25, 22 and 28 may be mounted in any suitable arrangement of bearings sup- 40 ported by the frame, and the shaft 22 and gears thereon, and coacting therewith are inclosed with the suitable casing 32.

- The casting 15 is also usually secured to a leg or frame member extending vertically along the outside of the tub. The tub is 45 also provided with a valve controlled outlet.

What I claim is:

1. A washing machine comprising a re- 50 ceptacle, a vibratory flexible and perforate diaphragm mounted in the receptacle for supporting the clothes, means for holding the rim of the diaphragm against movement relatively to the receptacle, the middle portion of the diaphragm being movable above and below the horizontal plane of its rim, 55 and actuating means connected to the middle of the diaphragm, substantially as and for the purpose described.

2. A washing machine comprising a re- 60 ceptacle, a vibratory flexible and perforate diaphragm mounted in the receptacle for

supporting the clothes, the diaphragm being in the form of a sheet formed with water passages, means for holding the rim of the diaphragm against movement relatively to the receptacle, substantially as and for the 65 purpose specified.

3. A washing machine comprising a re- ceptacle, a vibratory flexible and perforate diaphragm mounted in the receptacle for supporting the clothes, means for holding 70 the rim of the diaphragm against movement relatively to the receptacle, the diaphragm being in the form of a discoidal sheet and its central portion being movable below and above the plane of its rim, and actuating 75 means connected to the middle of the dia- phragm, the actuating means including a member located below the diaphragm and connected to the same centrally thereof, sub- stantially as and for the purpose set forth. 80

4. A washing machine comprising a re- ceptacle, a flexible and perforate diaphragm mountable in the receptacle and having an expandible and contractile rim formed with an inwardly extending loop, the receptacle 85 having means for coacting with the rim to hold the same from vibratory movement, means for actuating the diaphragm includ- ing members extending through said loop to the lower side of the diaphragm and the 90 member actuated by said means and connected to the central part of the diaphragm, substantially as and for the purpose de- scribed.

5. A washing machine comprising a re- 95 ceptacle, a vibratory flexible diaphragm mounted in the receptacle for supporting the clothes, means for holding the rim of the diaphragm against movement relatively to the middle of the diaphragm, the dia- phragm being formed with valve controlled 100 passages therethrough, and means connect- ed to the central portion of the dia- phragm for reciprocating the same relatively to its rim, substantially as and for the purpose 105 specified.

6. In a washing machine, a tub or recep- tacle, a discoidal perforate diaphragm in the receptacle, means for holding the rim of the diaphragm from movement and means 110 connected to the central part of the dia- phragm for reciprocating it from below the level of the rim to above said level and vice versa.

In testimony whereof, I have hereunto 115 signed my name, at Syracuse, in the county of Onondaga, and State of New York, this 17th day of November, 1919.

ROBERT LELAND KINCAID,
